UNITED STATES PATENT OFFICE

138,867

DESIGN FOR A FLASH OR SIGNAL LIGHT

Raymond L. Falge, Bethesda, Md.

Application July 13, 1944, Serial No. 114,386

Term of patent 7 years

(Cl. D48—24)

To all whom it may concern:

Be it known that I, Raymond L. Falge, a citizen of the United States, residing in Bethesda, Maryland, have invented a new, original, and ornamental Design for a Flash or Signal Light, of which the following is a specification, reference being had therein to the accompanying drawing, forming a part thereof.

In the drawing:

Fig. 1 is a side view.

Fig. 2 is a front end view, and

Fig. 3 is a rear end view of a flash or signal light, showing my new design.

I claim:

The ornamental design for a flash or signal light, as shown.

RAYMOND L. FALGE.
